UNITED STATES PATENT OFFICE.

CATHERINE MATHILDE VILLONTREIX, OF LIMOGES, FRANCE.

DESIGN FOR A PLATE OR SIMILAR ARTICLE.

43,240.

Specification for Design.

Patented Nov. 5, 1912.

Application filed June 7, 1912. Serial No. 702,369. Term of patent 7 years.

To all whom it may concern:

Be it known that I, CATHERINE MATHILDE VILLONTREIX, a citizen of France, residing at Limoges, France, have invented a new, original, and ornamental Design for Plates or Similar Articles, of which the following is a specification, reference being had to the accompanying drawing, forming part thereof.

The figure is a face view of a quarter of a

plate, the other three quarters consisting of repetitions of the design shown.

I claim—

The ornamental design for a plate or similar article, as shown.

CATHERINE MATHILDE VILLONTREIX.
